UNITED STATES PATENT OFFICE.

JONATHAN CAPSTACK, OF BARNESVILLE, OHIO.

IMPROVEMENT IN TWISTING-MACHINES.

Specification forming part of Letters Patent No. 171,548, dated December 28, 1875; application filed May 17, 1875.

To all whom it may concern:

Be it known that I, JONATHAN CAPSTACK, of Barnesville, in the county of Belmont and State of Ohio, have invented certain new and useful Improvements in Twisting-Machines; and I do hereby declare that the following is a full, clear, and exact description thereof, reference being had to the accompanying drawings, and to the letters of reference marked thereon, which form part of this specification.

The nature of my invention consists in the construction and arrangement of a spinning-machine, as will be hereinafter more fully set forth.

In order to enable others skilled in the art to which my invention appertains to make and use the same, I will now proceed to describe its construction and operation, referring to the annexed drawing, in which—

Figure 1 is a front elevation. Fig. 2 is a central vertical section on line x x , Fig. 1; and Fig. 3 is cross-section on y y , Fig. 1.

A represents the frame of my machine, in the lower part of which, near one side, are the journal-bearings for a drum or cylinder, B. On one of the journals of this drum is placed a pulley, a, connected by a rope or belt, b, with a large grooved pulley or wheel, C, secured on a counter-shaft, d. On this shaft is further secured a conical pulley, D, which is by a rope or belt, e, connected with a similar pulley, D', on the shaft f of the reel E. The drum or cylinder B is, by a cord or belt, h, connected with a pulley, i, on the lower end of a vertical spindle, m, having its bearings in the frame A. On this spindle are secured two horizontal disks or circular plates, G and G'. From the lower plate G project upward a series of short vertical spindles, n, on which the bobbins H are placed. In the upper disk G'

are made slots x, corresponding with the number of bobbins, and extending from the edge of the disk inward for a suitable distance, and at the inner end of each slot x is a larger slot, y, in which is placed a rubber shoe, s, attached to the end of a spring, p. The other end of this spring is secured to a plate or lever, t, pivoted on the disk G, and the free end of said lever operated upon by a key or button, w, in such a manner as to give more or less pressure of the shoe s in the end of the slot y. The threads from the bobbins H are inserted in the slots x y, and held by the tension-shoes s, and the threads then pass through the upper hollow end of the spindle m, through a guide, z, to the reel E.

The machine may be operated by crank, or a treadle applied to the drum or cylinder B, and the tension on the threads is easily regulated by the devices above described. By changing the position of the cord or belt e on the conical pulleys D D', more or less twist may be given to the yarn, as desired.

Having thus fully described my invention, what I claim as new, and desire to secure by Letters Patent, is—

In a spinning-machine, the tension-regulating device herein described, consisting of the rubber shoe s, spring p, pivoted plate or lever t, and button w, arranged as described, to operate on the thread in the slots x y of the disk G', as set forth.

In testimony that I claim the foregoing as my own I affix my signature in presence of two witnesses.

JONATHAN CAPSTACK.

Witnesses:

W. C. MCARTHUR,
THEODORE BROWN.
